UNITED STATES PATENT OFFICE.

LOUIS McCARTHY, OF BOSTON, MASSACHUSETTS.

DESIGN FOR AN INSULATOR.

SPECIFICATION forming part of Design No. 28,355, dated March 8, 1898.

Application filed January 18, 1898. Serial No. 667,111. Term of patent 14 years.

To all whom it may concern:

Be it known that I, LOUIS McCARTHY, a citizen of the United States, residing at Boston, in the county of Suffolk and State of Massachusetts, have invented and produced a new and original Design for Insulators, of which the following is a specification, reference being had therein to the accompanying drawing.

The accompanying drawing represents in elevation an insulator embodying my design.

The leading features of my design are the spherical body 1, the cylindrical portion, as 2, joined by a narrow or contracted neck, as at 3, to the spherical body 1, and the stem, as

4, projecting from the cylindrical portion 2 ¹⁵ on the side thereof opposite to the spherical body 1 and directed away therefrom.

Having thus described my design, what I claim, and desire to secure by Letters Patent, is—

The design for an insulator substantially as shown.

In testimony whereof I affix my signature in presence of two witnesses.

LOUIS McCARTHY.
